(57) **CLAIM**

The ornamental design for a speaker for a light bar, as shown and described.

DESCRIPTION

FIG. 1 is a perspective view of a speaker for a light bar, showing our new design.

FIG. 2 is a front elevation view thereof.

FIG. 3 is a right side elevation view thereof.

FIG. 4 is a top plan view thereof.

FIG. 5 is a rear elevation view thereof.

FIG. 6 is a left side elevation view thereof; and,

FIG. 7 is a bottom plan view thereof.

The broken line portions of FIGS. 1, 2, 4, and 7 are included to show unclaimed subject matter only and form no part of the claimed design.
